BRASSIÈRE

Fernand Desrochers, Quebec, Quebec, Canada,
assignor to Dominion Corset Company Limited,
Quebec, Quebec, Canada

Application January 25, 1951, Serial No. 207,761

1 Claim. (Cl. 2—42)

1

This invention relates to improvements in brassières.

One object of the invention is to provide a brassière having relatively wide end portions equipped with eyelets through which lacing is threaded to secure the brassière tightly in place around the body of the wearer, said end portions being reinforced in a novel manner to prevent wrinkling thereof when laced tightly together.

Another object is to provide a brassière of the kind described in which the end portions of the garment are provided with reinforced areas extending across substantially the full width of said end portions immediately adjacent the eyelets through which the lacing is threaded, said reinforced areas being of sufficient thickness to balance the thickness of the lacing in a manner which eliminates lacing bulges that might cause discomfort or show through the gown of the wearer.

Other objects, advantages and characteristic features of the invention will be more readily understood from the following detailed description of the accompanying drawings, in which—

Fig. 1 is a rear perspective view of a brassière embodying my invention. In this view, portions of the reinforced ends of the brassière are broken away to show concealed reinforcing elements.

Fig. 2 is a sectional view taken along the section line 2—2 of Fig. 1.

Fig. 3 is a sectional view taken along the line 3—3 of Fig. 1.

Fig. 4 is a sectional view taken along line 4—4 of Fig. 1.

Fig. 5 is a detail view of one of the eyelets tapes shown in the preceding figures.

Referring more particularly to the drawings, 5 designates a brassière provided with relatively wide reinforced end portions 6 equipped with eyelets 7 through which lacing 8 is threaded to secure the garment tightly around the body of the wearer. The reinforced areas of the end portions 6 are generally indicated at 9 in Fig. 1 and extend across substantially the full width of said end portions immediately adjacent the portions of the eyelets 7 through which the lacing 8 is threaded.

The preferred method of reinforcing the end portions 6 of the brassière and attaching the eyelets 7 is illustrated to advantage in Figs. 2 to 4 inclusive. As here shown, each end of the brassière is folded upon itself to provide a two-ply marginal edge 10 which overlaps and is secured to an eyelet tape 11 so that a portion of

the width of the tape projects beyond said edge 10 in the form of a flap 12. The tape 11 carries a row of eyelets 8 which have their anchoring loops 8a (Fig. 5) sewn to the tape and covered by the two-ply marginal end edge 10 of the brassière. A feather bone reinforcing element 13 is interposed between the anchoring loops 8a of the eyelets 8 and the covering two-ply marginal end edge portion 10 of the brassière. This reinforcing element is pocketed in place and held against lateral movement by two vertical rows of stitching 14 which secure the folded end edge 10 to the tape 11. Endwise or vertical movement of the reinforcing element is prevented by 15 horizontal rows of stitching 15 uniting the upper and lower margins of the folded edge 10 to the tape 11. The U-shaped lace-receiving portions of the eyelets 8 project beyond the folded end edge 10 of the brassière and overlie the inner portion of the flap 12 afforded by the projecting portion of tape 11.

One advantage of the reinforcing elements 13 is that they stiffen the end edges of the brassière in such manner as to prevent wrinkling 25 of the latter when the lacing is drawn tight to give a snug fit of the garment about the body of the wearer. Another advantage of these reinforcing elements is that they provide added thickness at the ends of the brassière which, by 30 balancing the thickness of the lacing, prevents the latter from forming bulges or ridges that might cause discomfort or show through the gown of the wearer.

In the present instance, each eyelet tape is 35 shown formed from a single strip of material (Fig. 5), having longitudinal marginal edges 11a and 11b folded inwardly over the central portion of the strip in overlapping relation with each other to provide three thicknesses of material 40 underlying the eyelet anchoring loops 8a which are sewn to the tape by stitching 16.

Having thus described the nature and a preferred embodiment of my invention it will be understood that various modifications may be 45 resorted to within the scope and spirit of the invention as defined by the appended claim.

The embodiments of the invention in which an exclusive property or privilege is claimed are defined as follows.

50 I claim:

A brassière having relatively wide end portions, eyelet tapes secured to said end portions so that portions of the width of the tapes project beyond said end portions to provide flaps, a reinforcing strip interposed between each end por-

tion of the brassière and an opposing portion of the tape secured to said end portion, a row of eyelets secured to each tape with the anchoring loops of the eyelets interposed between said tape and the reinforcing element opposed to said tape, said eyelets presenting lace-receiving portions projecting beyond the end portion of the brassière to which said tape is secured and overlying the flap portion of said tape, said reinforcing elements extending across substantially 10

the full width of the said end portions of the brassière.

FERD. DESROCHERS.
